United States Patent Office

Des. 210,065
Patented Feb. 6, 1968

210,065

SLIPPER

Basil D. Huff, Wilkes-Barre, Pa. (½ Charles Sonnenreich, 1501 Broadway, New York, N.Y. 10036)

Filed Dec. 6, 1966, Ser. No. 4,941

Term of patent 7 years

(Cl. D2—287)

FIG. 3

FIG. 1 is a side perspective view of a slipper showing my new design, the side opposite being substantially similar thereto.

FIG. 2 is a bottom plan view.

FIG. 3 is a plan view of the slipper in flat position with the laces removed.

I claim:

The ornamental design for a slipper, substantially as shown and described.
